UNITED STATES PATENT OFFICE.

MILTON E. THOMPSON, OF BARTOW, FLORIDA.

PLOTTER FOR DRAFTING.

SPECIFICATION forming part of Letters Patent No. 335,853, dated February 9, 1886.

Application filed September 14, 1885. Serial No. 177,098. (Model.)

To all whom it may concern:

Be it known that I, MILTON E. THOMPSON, of Bartow, in the county of Polk and State of Florida, have invented a new and Improved Drafting-Instrument, of which the following is a full, clear, and exact description.

The object of my invention is to provide a new and improved drafting-instrument for making perspectives and like drawings, which instrument can also be used for drawing parallel lines, &c.

Reference is to be had to the accompanying drawings, forming part of this specification, in which a plan view of my improved drafting-instrument is shown.

The invention consists in a special combination of straight-edges, pivots, and connecting-rods, as will be fully set forth herein-after, and then pointed out in the claims.

10 A, B, and C are three straight-edges or rules, of which the latter—which is between the two former—is provided with a longitudinal slot, C'.

The right-hand ends of the rules A and B are connected with the right-hand end of the rule C by the connecting-rods D, pivoted by the pivots a b c.

20 Two rods, E, each having a longitudinal slot, E', are pivoted to the left-hand ends of the rules A B C, and a pivot, F, is passed through the slot C' and the slots E' of the bars E.

Rods G are pivoted to the right-hand end of the rule C by the pivot e, and pivots g on the left-hand ends of the rods G are passed through the slots E' of the bars E.

Rods H are pivoted on the ends of the rules A and B by the pivots a b, and their left-hand ends are united by a pivot, h, passed through the slot C' of the rule C.

A rule, J, is hinged to the upper edge of the rule A, and to the rule J a curved slotted arm, K, is secured, through the slot of

which a binding-screw, L, is passed into the rule A. The several pivots are binding-screws for locking the several pieces in place in relation to each other. The top edges of the

rules A B converge to the same point in whatever position they may be. The rule B is secured parallel with the edge of the drawing-board, and the rule A is moved toward or from the same to get the desired lines. The

50 distances from the pivot F to the pivots e

must always be greater than the distances from the pivot e to the pivots a b. When the distances from the pivot F to the pivots e are equal to the distances from the pivot e to the pivots a b, a parallel rule is formed. The 55 edge of the rule A converges to the vanishing point, but not lines parallel with said edge. To remedy this, I have provided the additional rule J, which can be so adjusted that its continuation extends to vanishing point. 60 The radius of the distance from the vanishing point to the pivot F can easily be adjusted by moving or adjusting the pivot F a greater or less distance from the left-hand end of the rule C.

Having thus described my invention, what I claim as new, and desire to secure by Letters Patent, is—

1. The combination, with the rules A B C, of the rods D, connecting the rules A B C, 70 and the adjustable rods E, connecting rules A B C at the opposite ends, substantially as shown and described.

2. The combination, with the rules A B C, of the rods D, pivoted to the rules A B C, 75 and the slotted rods E, connecting the rules A B C at the opposite ends, substantially as herein shown and described.

3. The combination, with the rules A B C, the latter having the slot C' of the rods D, 80 connecting the rules A B C, the slotted rods E, pivoted to the rules A B, and the pivot F, passed through the slots C' and E' in the rule C and rods E, respectively, substantially as herein shown and described.

4. The combination, with the rules A B C, the latter having the longitudinal slot C' of the rods D, connecting the rules A B C, the slotted rods E, pivot F, the rods G, pivoted to the rule C, and the pivots g on the ends of the rods G, passed through the slots E', substantially as herein shown and described.

5. The combination, with the rules A B C, the latter having the slot C' of the rods D, connecting the rules A B C, the slotted rods E, 95 pivoted to the rules A B, the pivot F, the rods H, pivoted to the ends of the rules A B, and the pivot h, passed through the ends of the rods H and the slot C', substantially as herein shown and described.

6. The combination, with the rules A B C, the latter having the slot C', of the rods D, E, G, and H, substantially as herein shown and described.
- 5 7. The combination, with the rules A B C, of the rods D E, connecting them, the rule J, hinged on the rule A, the slotted arm K on the rule J, and the binding-screw L, substantially as herein shown and described.

MILTON E. THOMPSON.
